UNITED STATES PATENT OFFICE

94,896

DESIGN FOR A VEHICLE BODY

Firmen Johnson Hayden, Slippery Rock, Pa.

Application October 10, 1934, Serial No. 53,543

Term of patent 14 years

To all whom it may concern:

Be it known that I, Firmen Johnson Hayden, a citizen of the United States, residing at Slippery Rock, in the county of Butler and State of Pennsylvania, have invented a new, original, and ornamental Design for a Vehicle Body, of which the following is a specification, reference being had to the accompanying drawing, forming part thereof.

Figure 1 is a view in side elevation of a vehicle body, showing my new design.

Figure 2 is a view in top plan thereof.

Figure 3 is a front elevational view showing the louvres in the extreme front end of the body which are indicated by curved unshaded lines.

I claim:

The ornamental design for a vehicle body as shown and described.

FIRMEN JOHNSON HAYDEN.
